ILLUMINATED PEDESTRIAN TRAFFIC SIGNAL

Henry Dowding, Staten Island, N.Y., assignor to The Marbelite Company, Inc., Brooklyn, N.Y.

Filed Jan. 11, 1974, Ser. No. 432,756

Term of patent 14 years

Int. Cl. D10—06

U.S. Cl. D10—114

FIG. 1

FIG. 2

FIG. 3

FIG. 4

FIG. 5

FIG. 6

FIG. 1 is a front view of an illuminated pedestrian traffic signal of my new design showing the words "DON'T WALK" illuminated;

FIG. 2 is a front view of the illuminated pedestrian traffic signal showing the word "WALK" illuminated;

FIG. 3 is a side view of the illuminated pedestrian traffic signal;

FIG. 4 is a top view thereof;

FIG. 5 is a bottom view thereof; and

FIG. 6 is a rear view thereof.

I claim:

The ornamental design for an illuminated pedestrian traffic signal, as shown and described.
